CAKE OF SOAP OR THE LIKE

Olga M. Biallo, 430 E. 56th St.,
New York, N.Y. 10019

Continuation of abandoned design application Ser. No. 12,889, July 25, 1968. This application Jan. 29, 1970, Ser. No. 21,176

Term of patent 14 years

Int. Cl. D28—02

U.S. Cl. D73—1 A

FIG. 1 is a perspective view of a cake of soap embodying my new design;

FIG. 2 is a plan view showing either the top or the bottom of the cake of soap of FIG. 1, the top and bottom plan views being essentially the same;

FIG. 3 is a front elevational view as seen from line 3—3 in FIG. 2; and

FIG. 4 is a side elevational view as seen from line 4—4 in FIG. 2.

This application is a continuation of my copending application Ser. No. D. 12,889, filed July 25, 1968, now abandoned.

I claim:

The ornamental design for a cake of soap or the like, substantially as shown and described.
